W. WINKLER ET AL.

COMBINATION CURTAIN AND SHADE HOLDER

Filed Oct. 24, 1922

BY

F. Ledermann

ATTORNEY

UNITED STATES PATENT OFFICE.

WILLIAM WINKLER AND ARTHUR H. MILLER, OF BROOKLYN, NEW YORK.

COMBINATION CURTAIN AND SHADE HOLDER.

Application filed October 24, 1922. Serial No. 596,677.

To all whom it may concern:

Be it known that we, WILLIAM WINKLER and ARTHUR H. MILLER, citizens of the United States, and residents of Brooklyn, 5 in the county of Kings and State of New York, have invented certain new and useful Improvements in Combination Curtain and Shade Holders, of which the following is a specification.

10 This invention relates to combination curtain and shade holders, and the main object is to provide a device as mentioned which is designed to support a curtain pole and shade roller at the top of a window 15 frame in a neat manner, the general appearance of the brackets also serving as ornamentation.

Another object is to provide a modified type of bracket in which the curtain pole 20 supporting elements are extensible so as to enable a person to hang a curtain at any desired distance from the shade. An extensible curtain bar forms an important feature in this type of device, as the shades 25 when rolled up vary their diameters as to the length of the window.

These and other objects will become apparent in the description below, in which characters of reference refer to like-named 30 parts in the drawing.

Referring briefly to the drawing, Figure 1 is a side elevational view of the "left" bracket.

Figure 2 is a front elevational view of 35 the same.

Figure 3 is a side elevational view of the "right" bracket.

Figure 4 is a side elevational view of the 40 modified type of the bracket.

Figure 5 is a bottom plan view of the same.

Describing the drawing in detail, the numeral 1 indicates a base plate formed of a flat plate and has counter sunk holes 2 45 formed therein thru which screws pass, the latter securing the entire device to the window frame.

A flat bracket 3 is fixed to the base plate 1 and projects outwardly therefrom providing the support element for the shade 50 roller and curtain pole.

A shade roller is generally provided with a short centering pin at one end, and a square centering pin at the opposite end, the former being received in an opening of 55 the bracket shown in Figure 3, and the op-

posite bracket is provided with upright stays 6, separated by a channel 7 in which the square end of the shade roller is received.

The ends of both brackets have outwardly 60 curved arms 8 which provide cradles 9 in which the curtain pole 10 is supported. The stems 11 of the thumb screws 12 thread thru the arms above the cradle and retain the curtain pole in place.

The modified type of support bracket shown in Figures 4 and 5 has an angular plate 13 providing the base which is secured to the corner of the window frame and has counter sunk screw holes 14. A 65 sleeve 15 extends outwardly from the blank surface and has a hollow channel 16 passing therethru. A side wall of said sleeve has a slot 17 of relatively long length formed therein, the lower edge of said slot having 70 a series of spaced apart semi-circular notches 18, the purpose of which will be more fully hereinafter described.

An arm 19 extending upwardly at its outer end, has a cradle 20 formed between 80 the members 21, said cradle receiving the curtain pole 22, the latter being retained in said cradle by the thumb screw 24 in a similar manner to the preferred type here- 85 to described. The opposite end 25 of said arm 19 is slidably mounted in the sleeve 15 and has a pin 26 near its extreme end which rides centrally in said slot 17. A flexible wire flat spring 27 is fixed in said pin and extends angularly downward, 90 being formed into an enlarged head 28 by looping the end. Said head of the spring rides upon the lower edge of the slot 17 and is adapted to engage any of the notches 95 18 thereby retaining the arm in a correspond- 95 ing position.

The angular members 13 are each provided with lugs 29, one of which has a hole 100 therein which receives the pin end of a shade roller and the lug on the opposite bracket is provided with a recess 30 in which the square end of the shade roller is inserted.

We claim:

1. A device of the class described comprising an angular base plate, a hollow rectangular sleeve extending from said base and having a longitudinal slot therein on one side, said slot having a plurality of semi-circular notches formed on its lower edge, a rectangular arm fitting snugly in 110 and slidably in said sleeve, a cradle at the end of said arm adapted to receive a curtain

pole, and resilient means on said arm for engaging any of said notches for retaining the said arm in place.

2. A device of the class described comprising a base plate, a rectangular hollow sleeve extending therefrom having a longitudinal slot therein, said slot being closed at both ends, said slot having a plurality of semi-circular notches formed on its lower edge, an arm slideable in said sleeve, a pin projecting from one side of said sleeve and riding in said slot, a wire spring, a loop at

the free end of said spring engageable in any of the notches in the sleeve for retaining said arm in place, the loop of said spring being adapted to resiliently engage any of said notches, and means for supporting a shade roller and curtain pole.

Signed at New York in the county of New York and State of New York this 30 day of Sept. A. D. 1922.

WILLIAM WINKLER.
ARTHUR H. MILLER.
